UNITED STATES PATENT OFFICE

WILLIAM PARDEE SPRAGUE, OF LOS ANGELES, CALIFORNIA

APPLICATOR

Application filed December 26, 1928. Serial No. 328,472.

My invention relates to and has for its purpose the provision of an applicator particularly adapted, although not necessarily, for use in the treatment of hemorrhoids, fissures, 5 ulcerations, eczema and other pathological conditions of the anus and rectum, and by which various viscous fluids such as soothing emollients and ointments for example, can be distributed to these affected parts with the 10 utmost ease and dispatch and without injury or discomfort to the patient.

I will describe only one form of applicator embodying my invention, and will then point out the novel features thereof in claims.

15 In the accompanying drawing:

Fig. 1 is a view showing in longitudinal central section, one form of applicator embodying my invention, and

20 Figs. 2 and 3 are enlarged detail sectional views taken respectively on the lines 2—2 and 3—3 of Fig. 1.

25 Referring specifically to the drawing in which similar reference characters designate similar parts in each of the several views, my invention in its present embodiment comprises a body B constructed of hard rubber or other suitable material, bored longitudinally to provide a chamber 10 opening to one end of the body, and in which a charge of viscous 30 fluid such as ointments, is adapted to be received. From the other end of the body projects axially, a nozzle N in the form of an elongated cylindrical extension longitudinally tapered slightly from its point of connection with the body to its free end and adapted to be inserted into the anus and rectum or other parts to be treated.

35 The nozzle is bored to provide a longitudinally extending passage 11 therethrough communicating axially at one end with the chamber 10 and terminating at its other end in an axial discharge port 12. The nozzle N is further provided with a pair of radial ports 13 opening laterally of the nozzle at diametrically opposed points, and a second pair of radial ports 14 at right angles to the ports 13 and also opening laterally of the nozzle. The ports 13 and 14 communicate with the passage 40 11 at respectively different points along the

length of the nozzle, as is clearly shown in Fig. 1.

The chamber 10 is cylindrical in cross section, and a plunger P in the form of a cylindrical body of hard rubber or other suitable material is adapted to be inserted into the chamber and loosely fits the latter so as to permit the passage of air between the plunger and wall of the chamber during reciprocation of the plunger and thus prevent the trapping 55 of air in advance of the plunger during its inward or forward stroke and the creation of a vacuum in the chamber during the outward or return stroke of the plunger. Furthermore, by constructing the plunger of uniform diameter for a distance substantially equal to or greater than the length of the chamber 10, the possibility of the viscous fluid which might pass between the plunger and cylinder, 60 collecting behind the plunger and being withdrawn by the plunger from the cylinder, is obviated, thus preventing loss of the fluid as well as the smearing of anything with which the fluid comes in contact.

65 The plunger is provided with a head 15 on one end thereof, and the body with a continuous flange 16 on its open end; the head constituting an abutment for the thumb of an operator, while the flange constitutes an abutment for two adjacent fingers between which 70 the body B is adapted to be received, so that by pressure of the thumb upon the head the plunger can be readily forced inwardly of the chamber 10 to force the ointment in advance 75 of the plunger from the chamber to the passage 11 and from the latter through the discharge ports 12, 13 and 14. It will be noted that the inner end of the chamber 10 is tapered 80 as indicated at 17 to the confronting end of the passage 11 so as to force the fluid inwardly 85 towards the latter and thus minimize the escape of the fluid around the plunger.

90 It will be particularly noted that the lateral ports 13 are of less cross sectional area or size than the axial port 12 and that the lateral ports 14 are of less cross sectional area or size than the lateral ports 13, the proportionate sizes of the ports being such as to compensate for the viscosity of the viscous 95 fluid being used, and thus result in substan- 100

tially equal quantities of the viscous fluid being ejected from all the ports in response to inward movement of the plunger, to the end that the fluid will be uniformly distributed to the affected parts, and with the utmost ease and dispatch. The axial port 12 being the furthest remote from the application of pressure by the plunger P to the mass of viscous fluid in the chamber, must necessarily be the largest of the ports, as the resistance of the fluid to movement will be greater than at the lateral port 13 and 14, the resistance decreasing from the axial port 12 inwardly of the passage 11, so that by graduating the sizes of the ports in a predetermined relationship to their distances from each other and from the application of pressure to the mass of viscous fluid, the ejection of substantially equal quantities of the fluid from all the ports will be insured.

Although I have herein shown and described only one form of applicator embodying my invention, it is to be understood that various changes and modifications may be made herein without departing from the spirit of the invention and the spirit and scope of the appended claims.

I claim as my invention:

1. An applicator comprising a body having a chamber adapted to receive a charge of viscous fluid, an elongated nozzle projecting from the body and adapted to be inserted into the anus, the nozzle having a passage therethrough communicating at one end with the chamber and terminating at its other end in an axially disposed discharge port, the nozzle being provided with a plurality of lateral ports communicating with said passage at respectively different intervals along its length, and means for ejecting fluid from the chamber through said ports, the lateral ports being of less cross sectional area than the axial port and decreasing in their respective cross sectional areas in such proportion to the distances from the axial port, at which they communicate with said passage, that substantially equal quantities of the viscous fluid will be ejected through all ports in response to an actuation of the ejecting means.

2. An applicator comprising a body having a cylindrical chamber opening to one end of the body for the introduction into the chamber of a charge of viscous fluid, an elongated nozzle projecting axially from the other end of the body and having a longitudinally extending passage therethrough communicating at one end with the chamber and terminating at its other end in an axially disposed discharge port, the nozzle having a plurality of radial ports opening to the sides of the nozzle at circumferentially spaced points and communicating with said passage at intervals along its length, and a reciprocating plunger loosely fitting within the

chamber for ejecting the contents of the latter through said ports, the radial ports being of less cross sectional areas than the first mentioned port and decreasing in their respective cross sectional areas in such proportion to the distances from the first mentioned port and from each other at which they communicate with said passage as to compensate for the viscosity of the fluid and admit of substantially equal quantities of the fluid being ejected through all ports in response to an actuation of the plunger.
